(57) **CLAIM**

The ornamental design for a support rail, as shown and described.

DESCRIPTION

FIG. 1 is a perspective view of a support rail;

FIG. 2 is front elevational view of a support rail;

FIG. 3 is a rear elevational view of a support rail;

FIG. 4 is a left side elevational view of a support rail;

FIG. 5 is a right side elevational view of a support rail;

FIG. 6 is a top plan view of a support rail; and,

FIG. 7 is a bottom plan view of a support rail.

The broken lines depict portions of the support rail that form no part of the claimed design.
